Primary Examiner — Michael C Stout*Assistant Examiner* — James T Tyree(74) *Attorney, Agent, or Firm* — Perry Hoffman(57) **CLAIM**

The ornamental design for a toy projectile launcher apparatus as shown and described.

DESCRIPTION

FIG. 1 is a front perspective view of the toy projectile launcher apparatus of the instant design;

FIG. 2 is a rear perspective view thereof;

FIG. 3 is a right side elevational view thereof;

FIG. 4 is a left side elevational view thereof;

FIG. 5 is a rear view thereof;

FIG. 6 is a front view thereof;

FIG. 7 is a top view thereof; and,

FIG. 8 is a bottom view thereof.

The broken lines shown and unshaded areas adjacent to them are included for the purpose of illustrating the unclaimed portions of the article and form no part of the claimed design.
